UNITED STATES PATENT OFFICE.

JAMES WHITELAW, OF ST. LOUIS, MISSOURI, ASSIGNOR OF ONE-HALF TO
ST. LOUIS TYPE FOUNDRY, OF SAME PLACE.

CARD CUTTING OR STRIPPING MACHINE.

SPECIFICATION forming part of Letters Patent No. 234,829, dated November 23, 1880.

Application filed October 6, 1880. (No model.)

To all whom it may concern:

Be it known that I, JAMES WHITELAW, of the city of St. Louis, in the State of Missouri, have invented certain new and useful Improvements in Card Cutting and Stripping Machines, of which the following is a full, clear, and exact description, reference being had to the accompanying drawings, making part of this specification.

10 My improvement applies more especially to the described apparatus for clamping the card (or other material) in place, and at the same time holding the circular cutter in contact with the fixed knife.

15 In the drawings, Figure 1 is a top view of the machine. Figs. 2 and 3 are enlarged part transverse sections at $\alpha\alpha$, Fig. 1, showing the clamping-bar in its upper and lower positions, respectively. Fig. 4 is a detail perspective view 20 enlarged. Fig. 5 is a detail perspective view of the end of the clamping-bar. Fig. 6 is a detail back view of part of the table, showing one of the removable guides in position.

The machine, in the form shown, is intended 25 to stand on a bench.

A is the table or base-plate, having at the two front corners standards B B, with guide-slots b, to receive the lugs c at the ends of the clamping-bar C.

30 The clamping bar or rail has a strictly-vertical movement, being guided by the lugs c and by the sides of the slots c' at its ends, through which pass the pivot-pins D of the cam-bar E.

35 The pivot-pins D are fixed to the standards by nuts d d bearing against the sides of the standards and screwing upon the pins, and the pins are made adjustable in the standards in vertical slots, through which they pass.

40 At both ends of the cam-bar E are cams F, which work between flanges c² c² at each end of the clamping-bar, to raise and lower the same.

The cams are thrown into the position 45 shown in Figs. 2 and 4 by a spring, G, attached at the upper end to a lug, e, at the back of the cam-bar, and attached at the

lower end to the table A. Thus the spring lifts the cams and with them the clamping-bar, so that the card-board or other material 50 to be cut can be introduced or be moved beneath the clamping-bar.

H is the knife, fixed in the front edge of the table. I is a circular cutter, which runs along in contact with the edge of the knife.

55 The circular cutter is axially pivoted to a head, J, sliding upon a round bar, K, whose ends are attached to the standards B. The head J has capacity for lateral and oscillatory movement on the bar K, to bring the edge of 60 the circular turning cutter in contact with the edge of the knife and allow it to travel along it. The head is moved by means of a handle, j.

L is a lug upon the head J, giving bearing 65 to a short shaft, i, having at the fore end an arm, M, with a handle, m, which is in proximity to the handle j, so that it can be grasped at once with the same, and by the pressure of the hand the arm M is drawn down and draws 70 down the roller-arm N at the other end of the shaft i.

The arm N carries a wheel or roller, O, which bears upon a flange, E', extending 75 along and forming the upper front edge of the cam-bar. The pressure of the wheel on the descent of the arm N forces down the front edge of the cam-bar and depresses the cams F, and with them the clamping-bar, into the position shown in Fig. 3.

80 The reaction upon the head J of pressure of the wheel O upon the cam-bar acts to tilt out the head J and force the rotary cutter against the knife.

85 When the grasp upon the handles j m is loosened, the spring G throws the cams and bars into the position shown in Fig. 2, allowing the card or other material to be moved beneath the clamping-bar.

P is a gage-bar, supported on two slide-rods, 90 R, adjustable in the table A, and held in position the required distance from the knife by set-screws S.

The table has transverse channels a perpen-

dicular to the edge of the knife, fitted to receive guide-strips a' , to keep the material square on the table.

I claim as my invention—
5 The combination, with a clamping-bar, of a cam-bar, E, acting to raise and lower the clamping-bar, and operated in its downward movement by a pressure-wheel, O, on shaft i ,

having bearing upon the oscillating cutter-head J, and actuated by handle M m, for the purpose set forth.

JAMES WHITELAW.
